[57] CLAIM

The ornamental design for a transparent fishing hook, as
shown.

DESCRIPTION

FIG. 1 is a side view of the transparent fishing hook of
this invention.

FIG. 2 is a front view partly in elevation and partly in
cross-section of the transparent fishing hook of this
invention.

FIG. 3 is a top view of the transparent fishing hook of
this invention.

FIG. 4 is a cross-section of the transparent fishing hook
of this invention along plane 4—4 of FIG. 1.

FIG. 5 is a cross-sectional view of the transparent fish-
ing hook of this invention along plane 5—5 of FIG. 1.

FIG. 6 is a cross-sectional view of the transparent fish-
ing hook of this invention along plane 6—6 of FIG. 1.

FIG. 7 is a cross-sectional view of the transparent fish-
ing hook of this invention along plane 7—7 of FIG. 1.

FIG. 8 is a cross-sectional view of the transparent fish-
ing hook of this invention along plane 8—8 of FIG. 1.

FIG. 3

FIG. 8
